(57) **CLAIM**

The ornamental design for a cellular phone display screen with graphical user interface, as shown and described.

DESCRIPTION

1. Cellular phone display screen with graphical user interface

1.1 is a front view of the cellular phone display screen with graphical user interface.

In Reproduction 1.1 the broken lines are for the purpose of illustrating portions of the cellular phone display screen that forms no part of the claimed design.

1 Claim, 1 Drawing Sheet
